REFLECTOR

Louis A. Bean, Denver, Colo.

Application November 13, 1933, Serial No. 697,751

3 Claims. (Cl. 240—103)

This invention relates to light-reflecting devices and apparatus, and more particularly to such devices and apparatus employed for the illumination of relatively large areas, and has as 5 an object to provide a novel and improved reflector for the purpose set forth.

A further object of the invention is to provide an improved reflector operable in combination with a light source to illuminate a relatively 10 large area with high efficiency.

A further object of the invention is to provide an improved reflector operable to efficiently diffuse the light emanating from a source over a relatively large area.

15 A further object of the invention is to provide an improved combination of curved reflecting surfaces operable to efficiently diffuse the light emanating from a source over a relatively large area.

20 A further object of the invention is to provide an improved combination of curved reflecting surfaces operable to enhance the uniform character of light projected thereby.

A further object of the invention is to provide 25 an improved combination of curved reflecting surfaces operable to minimize glare in the light projected thereby.

A further object of the invention is to provide 30 an improved combination of curved reflecting surfaces operable to efficiently project light with a minimum of glare-producing parallel or convergent rays.

A further object of the invention is to provide 35 an improved unitary reflector assembly including improved means for adjustably mounting the said assembly in operative position.

A further object of the invention is to provide 40 an improved reflector particularly adapted for flood-lighting purposes and arranged for convenient, adjustable mounting.

45 My invention consists in the construction, arrangement and combination of elements herein-after set forth, pointed out in my claims and illustrated by the accompanying drawing, in

Figure 1 is a front elevation of my improved reflector positioned for practical use. Figure 2 is a rear elevation of the showing of Figure 1. Figure 3 is a section taken on the vertical me- 50 dian line of the showing of Figure 1. Figure 4 is a half-section taken horizontally of the showing of Figure 1.

In the construction of the improved reflector as shown, the numeral 10 designates the body 55 portion or shell of the reflector, which element

is formed integrally of any suitable material, such as metal, by moulding, stamping, or otherwise, as may be found most desirable. The shell 10 is approximately circular in elevation and is preferably finished with an annular rim or 5 flange 11 to provide convenient means for mounting a protecting lens in closing relation with the concaved portion of the reflector. The area of the shell 10 within the rim 11 is concaved to a vertex positioned in the vertical me- 10 dian plane of said shell and some distance below the center pertaining to the rim 11, the reflecting surface thus developed being a smooth concavity presenting a curvature, where intersected by the vertical median plane, closely cor- 15 responding with a segment of a convolute or spiral positioned with its lesser radiants lowermost, which central curve is connected to the rim 11 on each side by means of smooth parabolic and arcuate surfaces, the exact character 20 of the curves in any given horizontal section varying between a true parabola and a true circular arc according to the vertical location of the specific section. The reflector above described is particularly designed for use in the 25 flood-lighting of relatively large areas when mounted at a considerable elevation above the ground and with its frontal plane substantially vertical, the median plane of the reflector containing the spiral segment being thus vertically 30 positioned with its portion of greater radiants uppermost. The spiral section is employed to provide a more uniform and intense flood-lighting effect on the area to be illuminated than is possible of attainment through reflectors of 35 symmetrical curvature in the vertical median plane, since the diverging area of the spiral curve produces an ever-changing incidence to the light rays impinging thereon and reflects said rays at angles productive of an exceptional- 40 ly wide and long area of illumination on a surface perpendicular to the plane containing said spiral. The curves appearing in horizontal planes intersecting the reflector and in inter- 45 connecting relation between the circular outline of the frontal plane and the central spiral curve are smooth and continuous and hence are em- pirically determined according to their vertical disposition relative to the assembly, it being obvious that the majority of the horizontal 50 curves may be approximately parabolic without presenting any undue distortion of the smooth and continuous nature of a given curve, and that such curves will present a variation in their constants and mathematical characteristics ac- 55

cording to their vertical location relative to the circular outline and spiral segment, the majority of such curves in the mid and lower portions of the reflector being generally parabolic while the 5 horizontal curves of the upper portion in the reflector approach an arcuate character as the depth of the reflector decreases in proportion to the chord opening of the frontal outline. Formed on and interrupting the concavity above 10 described, a plurality of ridges 12, in this instance twelve in number, radiate fanwise from a common point, located by intersection of the vertical median plane with the lower inner edge of the rim 11, along and upwardly of the concavity described to uniform spacing of their upper ends on both sides of the vertical median plane along the junction of the concaved surfaces with the upper portion of the rim 11, the wedge-shaped, vertically-disposed surfaces thus 15 formed between adjacent ridges 12 being smoothly concaved from crest to crest of said ridges.

The improvement thus far described presents a complete and operative reflector which may be 20 mounted in any suitable and desired manner in operative relation with a source of light. However, to obviate certain difficulties of installation and to provide a complete, operative assembly, a mounting extension 13 is suitably 25 formed of metal, or other proper material, and provided with an open upper end shaped to receive the shell 10 and support the latter in vertical position, said extension and shell being rigidly secured in proper interrelation by means of 30 screws (not shown) or any other suitable fastening means or devices. The extension 13 is formed with aligned, laterally-extending, cylindrical ears 14 which are adapted to be received in and held by suitable clamps (not shown), thus mounting the assembly for adjustment of 35 the reflector shell through a vertical arc. A transverse web 15 is formed in the central lower portion of the extension 13 and serves as a support for an electric light socket 17 thus positioned within said extension beneath the shell 10, said socket aligning with a hole 16 formed in the lower portion of said shell 10, through 40 which hole an electric light bulb 18 may be inserted for operative engagement with the socket 17, the said bulb being thus positioned and held 45 in proper relation with the reflecting surfaces of said shell, adjusting means 19 preferably being provided between the socket 17 and web 16 to facilitate proper positioning of the light 50 source. Connection between the socket 17 and a source of electrical energy may be had by suitable insulated conductors, indicated at 20, which enter the extension 13 through one or the other of the ears 14. A removable and replaceable 55 housing member 21 is preferably provided on the lower portion of the extension 13 in position to provide access to the base of the socket 17 and connections therewith, the said extension 13, housing 21 and exterior of the shell 10 preferably being so shaped and finished as to interfit in a close approximation of a shell, as is 60 clearly illustrated in Figure 2.

In the operation of the improvement shown 65 and described, the socket 17 is so adjusted as to position the light source immediately in front of the reflector vertex and well within the concavity limited by the surface plane of the rim 11, thus placing the light source between the reflector surface and the centers of any circular 70 arcs or the foci of any parabolic arcs which may

be found in the reflector surface apart from the narrow wedge-shaped surfaces between the ridges 12, and said light source is, in respect of 5 said wedge-shaped surfaces, farther removed from the reflecting surfaces than are the centers or foci of said wedge-shaped areas, so that, the light source being as it were out of focus, no concentration of parallel or converging rays 10 is possible from the reflector and the light projected therefrom is substantially free from glare. 15 The main reflecting surface of the shell 10 projects a soft, diffused light throughout a relatively wide vertical and horizontal spread and the grouped, wedge-shaped reflecting surfaces project rays in every direction through the beam 15 deriving from the main surface, said rays intersecting other rays in an infinity of points having no possible common locus and effectively eliminating shadows, streaks and areas of weak illumination in the field deriving from the main 20 surface. The illumination thus produced is particularly well adapted for flood-lighting purposes and is exceptionally efficient in that the freedom from dark spots and weak areas permits adequate illumination with lights of relatively low 25 energy consumption.

Since many variations and modifications of the specific form, construction and arrangement of the elements shown and described may be had without departing from the spirit of my invention, I wish to be understood as being limited 30 solely by the scope of the appended claims rather than by any details of the illustrative showing and foregoing description.

I claim as my invention—

1. In a shell-like reflector having a frontal plane, a reflecting surface concaved rearwardly of said frontal plane, said surface being defined by a circular outline at its marginal intersection with said frontal plane, a central vertical strip 40 in the central vertical plane perpendicular to said frontal plane conforming in outline with a segment of a mathematical spiral, and said spiral joined to said circular outline by concaved areas such that every horizontal section thereof 45 is a generally smooth curve intersecting said spiral and symmetrical to the plane containing said spiral, said reflector having a total depth not exceeding one half the diameter of its frontal opening.

2. In a concaved, shell-like reflector having a frontal plane, a reflecting surface concaved rearwardly of said frontal plane, said surface being defined by a circular outline at its marginal intersection with said frontal plane, a central vertical strip in the central vertical plane perpendicular to said frontal plane conforming in curvature with a segment of a mathematical spiral disposed with its axis parallel with, forwardly of and below the center of the circular 60 outline in said frontal plane, and said spiral joined to said circular outline by concaved areas such that every horizontal section thereof is a generally smooth curve intersecting said spiral and symmetrical to the plane containing said 65 spiral, said reflector having a total depth not exceeding one half the diameter of its frontal opening.

3. In a concaved, shell-like reflector having a 70 frontal plane, a principal reflecting surface concaved rearwardly of said frontal plane, said surface being defined by a circular outline at its marginal intersection with said frontal plane, a central vertical strip in the central vertical plane perpendicular to said frontal plane conforming 75

in outline with a segment of a mathematical spiral, and said spiral joined to said circular outline by concaved areas such that every horizontal section thereof is a generally smooth curve intersecting said spiral and symmetrical to the plane containing said spiral, and supplementary reflecting surfaces formed on said principal surface as smoothly concaved areas between and interconnecting ridges traversing said

principal surface along lines marking the intersections of planes perpendicular to said frontal plane and diverging upwardly from the lower intersection of said spiral curve with said marginal outline with said principal surface, said principal reflecting surface having a total depth not exceeding one half the diameter of its frontal opening. ⁵
